PACKAGING TRAY

Henry R. Vigue, 18 Pleasant St., Waterville, Maine

Filed Jan. 19, 1965, Ser. No. 83,499

Term of patent 14 years

(Cl. D58—13)

Fig. 1.

FIG. 1 is a top plan view of a packaging tray showing my new design;

FIG. 2 is a side elevational view thereof;

FIG. 3 is a sectional elevational view on line 3-3 of FIG. 1; and

FIG. 4 is an end elevational view thereof.

I claim:

The ornamental design for a packaging tray, as shown and described.
